REFRIGERATION

Gustav Mårten Blomqvist, Stockholm, Sweden,
assignor, by mesne assignments, to Servel, Inc.,
New York, N. Y., a corporation of Delaware

Application February 3, 1940, Serial No. 317,056

18 Claims. (Cl. 62—5)

My invention relates to refrigeration, and more particularly to refrigeration systems of an absorption type in which refrigerant fluid is expelled out of solution by heating.

In refrigerators of the household type it is desirable to provide separate cooling elements for space cooling and for the production of ice cubes and other frozen matter. The cooling elements are preferably connected in such a manner in a refrigeration system that the cooling element primarily effecting space cooling operates at a higher temperature than the cooling element primarily employed for freezing ice cubes and the like. In many instances it is desirable to increase the refrigerating effect produced by the space cooling element without increasing the refrigerating effect produced by the lower temperature cooling element. This is true when there is no need for ice cubes. There are also times when it is desirable to hasten the production of ice cubes and the like without increasing the refrigerating effect produced by the space cooling element.

It is an object of the invention to provide the improvement in refrigeration systems of the absorption type whereby a plurality of cooling elements employed for space cooling and for the production of ice cubes may be controlled so that the refrigerating effect produced by one cooling element may be increased without increasing the refrigerating effect produced by another cooling element.

The above and other objects and advantages of the invention will be better understood from the following description taken in conjunction with the accompanying drawing forming a part of this specification, and of which the single figure more or less diagrammatically illustrates a refrigeration system embodying the invention.

Referring to the drawing, a first generator 10 includes an inner hollow member 11 surrounded by an outer shell 12. A second generator 13 is connected to the lower part of shell 12. A baffle 14 is provided within shell 12 just above the connection thereto of generator 13. This baffle extends approximately half way across the shell. A similar baffle 15 is disposed within the shell 12 below and on the opposite side from baffle 14.

Located within the hollow member 11 are four electric heating elements *a*, *b*, *c* and *d*. Element *a* is located within a portion of the member 11 which extends below and beyond the lower end of the shell 12. Element *b* is located within the portion of member 11 above the lower end of the shell and below the baffle 15. Element *c* is lo-

cated between the baffles 14 and 15, while element *d* is disposed above the baffle 14. One terminal of each of the heating elements is connected to one side 16 of an electric circuit 17 in which are provided a thermostatic switch 18 and a manual switch 19. The other terminal of element *a* is connected directly to the other side 20 of the circuit 17, so that current is supplied to this element when switches 18 and 19 are closed. The other terminals of heating elements *b*, *c*, and *d*, are connected to contacts 21, 22 and 23, respectively, of a multiple switch. Adjacent to each of these contacts are contacts 24, 25 and 26, respectively, each of which is connected to the side 20 of the circuit 17. The multiple switch includes a rotatable contact arm 27 which, in the position shown, bridges contacts 21 and 24, thereby closing the circuit of heating element *b*. Arm 27 may be rotated from the position shown so that it will bridge either contacts 22 and 25 or contacts 23 and 26, thereby closing the circuits of elements *c* or *d*, respectively.

Connected to the upper part of generator 10 is a conduit 30 provided with heat transfer fins 31. Conduit 30 is connected to the upper end of a first condenser 32, the lower end of which is connected by a conduit 33 with an evaporator 34 provided with heat transfer fins 35 and arranged for cooling the space within cabinet 36.

A conduit 37, which extends upward from the upper end of generator 13 and is provided with heat transfer fins 38 at its lower portion, is connected to the upper end of a condenser 39. The lower end of condenser 39 is connected by a conduit 40 to an evaporator 41 including a pipe coil arranged to absorb heat from ice trays 42 supported within a substantially closed shell 43.

A conduit 44 connects the upper end of evaporator 41 to a chamber 45 formed in the end of a gas heat exchanger 46. A plurality of tubes 47 connect chamber 45 with a similar chamber 48 at the other end of the heat exchanger. The tubes 47 are supported by headers 49 and 50 which separate the chambers 45 and 48 from a central space 51. The lower end of evaporator 41 is connected at 52 to space 51.

A conduit 53 extends upward from space 51 and communicates with the upper part of evaporator 34 at the same end to which conduit 33 is connected. A conduit 54 is connected to the opposite end of evaporator 34 and to the space 51. A vertical baffle 55 extends across the bottom of evaporator 34 near this end and a conduit 56 extends downward from the upper evaporator at

the right of the baffle 55 and is connected at its lower end to conduit 40.

Conduits 33 and 40 both extend upwardly beyond their connections to condensers 32 and 39, respectively, and at their upper ends are connected to one end of a pressure vessel 57. A conduit 58 connects the other end of pressure vessel 57 and the space 51.

A conduit 60 connects space 48 of the gas heat exchanger to the upper end of an absorber 61. The lower end of the absorber is connected to the space 51 by a conduit 62. The lower end of conduit 62 is also connected to a vessel 63 from the bottom of which extends a conduit 64 connected to the outer jacket 65 of a liquid heat exchanger 66.

A conduit 67 connects the other end of the jacket to a pipe coil 68 which forms a thermosyphon pump and is wound around that portion of hollow member 11 projecting below shell 12 and within which is located the heating element *a*. A conduit 69 connects the upper end of coil 68 to the upper part of generator 13. One end of a conduit 70 is connected to an upper part of generator 10 and extends within jacket 65 and the other end thereof is connected to the upper end of absorber 61.

A thermostatic element 71 is located within the refrigerator cabinet 36 and is connected by a tube 72 to a diaphragm chamber 73. The diaphragm within chamber 73 is so connected to the switch 18 as to open the switch when the temperature of the thermostatic element 71 has fallen to a predetermined value, and to close the switch when the temperature of the element rises above this value. Opening of this switch opens the circuits of all the heating elements.

The above described apparatus operates as follows:

Assuming that the switch 19 is closed and that the temperature of the thermostatic element 71 is sufficiently high so that the switch 18 is also closed, current will be supplied to the heating element *a*. The heat generated by this element serves to heat the liquid within the coil 68 sufficiently to vaporize a portion of this liquid. The vapor bubbles thus formed serve to raise the remaining liquid through the conduit 69 to the upper part of generator 13. With the contact arm 27 in the position shown, the circuit of heating element *b* is closed. The heat produced by this element serves to heat the solution of refrigerant, such as ammonia, dissolved in absorption liquid, such as water, in the lower part of the jacket 12 below the baffle 15 and hence causes refrigerant to be driven from the solution in the form of vapor bubbles. Baffles 15 and 14 cause these bubbles of refrigerant vapor to pass into the lower end of the generator 13. The bubbles travel upwardly through the liquid in this generator and the vapor passes through the conduit 37 to the condenser 39. The vapor is cooled somewhat by the fins 38, which causes the condensation of any water which may have been vaporized. In the condenser 39 the vapor is further cooled and the refrigerant is thereby liquefied. This liquid flows from the lower end of the condenser 39 through the conduit 40 to the upper end of the evaporator 41.

In the evaporator the liquid refrigerant flows into the presence of an inert gas, such as hydrogen, which enters through the conduit 44. Refrigerant in evaporator 41 evaporates and diffuses into the inert gas to produce a refrigerating effect, with consequent absorption of heat

from the surroundings. The rich gas mixture of refrigerant and hydrogen passes downwardly through the evaporator 41 and into the space 51 of the gas heat exchanger 46. The rich gas flows through this space around the tubes 47 and through the conduit 62 to the lower end of the absorber 61.

Weak absorption liquid is supplied to the upper end of the absorber by the conduit 70 and flows downwardly countercurrent to the gaseous mixture. The refrigerant is absorbed by the weak solution, while the inert hydrogen is not absorbed and flows from the upper end of the absorber through the conduit 60 to the space 48 in the gas heat exchanger. From here it flows through the tubes 47, space 45 and conduit 44 back to the upper end of the evaporator 41.

The strong absorption solution formed in the absorber flows from the lower end thereof through vessel 63, conduit 64, jacket 65 and conduit 67 to the coil 68. As previously described, the heating of the solution in this coil by means of the heating element *a* lifts it to the upper end of the generator 13. The solution flows downwardly through the generator into the lower part of jacket 12 and thence upwardly through the jacket and through the conduit 70 back to the upper end of the absorber 61.

Under the conditions above described refrigerant is supplied chiefly to the ice freezing evaporator 41 and little or no refrigerant is supplied to the cabinet cooling evaporator 34. Hence, substantially the entire capacity of the apparatus is concentrated on freezing ice with the result that ice may be frozen very rapidly.

If, on the other hand, it is desired to rapidly chill the interior of the cabinet 36, the contact arm 27 is rotated so as to bridge the contacts 23 and 26, whereby current is supplied to the heating element *d*. Inasmuch as this element is located above the lower end of the generator 13 and above the baffle 14 the refrigerant vapor produced by the heating effect of the element *d* passes upwardly through the jacket 12 and through the conduit 30 to the condenser 32. The vapor is here liquefied and the liquid flows from the lower end of the condenser through the conduit 33 to the cabinet cooling evaporator 34. Inert gas is introduced into this evaporator through the conduit 53, with the result that the refrigerant evaporates within the evaporator 34 and absorbs heat from the interior of the cabinet. If more liquid refrigerant is supplied to the evaporator than is evaporated therein, it overflows the baffle 55 and is conducted through the conduit 56 to the conduit 40. The gaseous mixture of refrigerant and hydrogen formed in the evaporator 34 flows therefrom through the conduit 54 to the space 51 and thence through conduit 62 to the absorber 61, as previously described.

Under these conditions practically no refrigerant is supplied from the generator 13 to the evaporator 41 and consequently the entire capacity of the apparatus is made available for reducing the temperature within the cabinet.

Since the inert gas flows first through evaporator 41 and then flows through evaporator 34 after leaving evaporator 41, the gas in evaporator 34 contains a greater amount of ammonia vapor than the gas in evaporator 41. The partial pressure of ammonia vapor is therefore higher in evaporator 34 than in evaporator 41, and evaporation of liquid ammonia takes place at a higher temperature in evaporator 34 than in evaporator 41.

The evaporator 41 is provided with a limited heat transfer surface and is primarily employed for the production of ice cubes and the like. The evaporator 34 is provided with the heat transfer fins 35 to provide a relatively extensive heat transfer surface and is primarily employed for space cooling.

Under normal operating conditions, when it is desired to chill both the cabinets and freeze ice, the contact arm is rotated so as to bridge the contacts 22 and 25, thereby supplying current to the element c. This element is so located with respect to the lower end of the generator 13 and the baffle 14 that the bubbles of refrigerant produced as a result of the heating effect of the element flow partially into the generator 13 and partially around the right hand edge of the baffle 14 into the upper part of the generator 10. Consequently, refrigerant vapor is supplied to both of the condensers 32 and 39, which in turn supply liquid refrigerant to both the evaporators 34 and 41. Hence, both of these evaporators absorb heat. Under these conditions the vapor flowing through conduit 53 to the evaporator 34 is a mixture of hydrogen and refrigerant, which is produced in evaporator 41, but, due to the fact that evaporator 41 receives only about half as much refrigerant as it does when element b is energized, this mixture is not saturated with refrigerant vapor and its introduction into the presence of the liquid refrigerant in evaporator 34 serves to reduce the partial pressure of the refrigerant therein sufficiently to cause it to evaporate.

Thus it will be seen that I have provided an apparatus wherein the supply of refrigerant to the two evaporators may be controlled independently in such a manner that all of the refrigerant may be supplied to either evaporator, or it may be divided between the two.

While I have shown and described one more or less specific embodiment of my invention, it is to be understood that this has been done for the purpose of illustration only and is not to be considered as limiting the scope of my invention, which is to be determined by the following claims.

What is claimed:

1. In an absorption refrigerating apparatus, a pair of generators connected together for series flow of liquid therethrough, means for supplying absorption solution rich in refrigerant to the first generator, means for withdrawing absorption solution weak in refrigerant from the second generator, a low temperature evaporator, a higher temperature evaporator, conduit means for connecting said first generator to said low temperature evaporator, conduit means for connecting said second generator with said higher temperature evaporator, a condenser disposed in each of said conduit means, and means for controlling refrigerant vapor expulsion in said generators.

2. In an absorption refrigerating apparatus, a pair of generators connected together for flow of liquid therethrough, a pair of evaporators, separate conduit means connecting the respective generators and evaporators together, a condenser disposed in each conduit means, heating means for independently heating each of said generators, and a common heating means for heating both of said generators.

3. In an absorption refrigerating apparatus, a pair of generators connected together for flow of liquid therethrough, means including a vapor-liquid lift for conducting absorption solution rich in refrigerant to one of the generators, means

for withdrawing absorption solution weak in refrigerant from the other generator, a pair of evaporators, separate conduit means connecting the respective generators and evaporators together, a condenser disposed in each conduit means, heating means for said vapor-liquid lift, and heating means for independently heating each of said generators.

4. In an absorption refrigerating apparatus, a pair of generators connected together for flow of liquid therethrough, means including a vapor-liquid lift for raising absorption solution rich in refrigerant to one of the generators, means for withdrawing absorption solution weak in refrigerant from the other generator, a pair of evaporators, separate conduit means connecting the respective generators and evaporators together, a condenser disposed in each conduit means, a heater for said vapor-liquid lift, a common heater for both of said generators, and additional heaters each of which is primarily adapted for use with one of said generators.

5. Generator means for an absorption refrigerating apparatus including a vertically extending hollow member, a shell around said hollow member forming therewith an annular space, a tubular member connected to said space adjacent to one end thereof, a first baffle means extending from the side of said shell part way across said space immediately above the point of communication therewith of said tubular member, a second baffle means extending from the opposite side of said shell part way across said space below said point of communication, a first heating means within said hollow member above the upper baffle means, a second heating means within said hollow member between said baffle means, and a third heating means within said hollow member below the lower baffle means.

6. Generator means for an absorption refrigerating apparatus including a vertically extending hollow member, a shell around said hollow member forming therewith an annular space, a tubular member connected to said space adjacent to one end thereof, a first baffle means extending from the side of said shell part way across said space immediately above the point of communication therewith of said tubular member, a second baffle means extending from the opposite side of said shell part way across said space below said point of communication, a first heating means within said hollow member above the upper baffle means, a second heating means within said hollow member between said baffle means, a third heating means within said hollow member below the lower baffle means, said hollow member having a portion extending below said shell, a thermo-syphon pump in heat exchange relation with said portion, and a fourth heating means within said portion.

7. Generator means for absorption refrigerating apparatus including a vertically extending hollow member, a shell around said hollow member forming therewith an annular space, a tubular member connected to said space adjacent to one end thereof, a first baffle means extending from the side of said shell part way across said space immediately above the point of communication therewith of said tubular member, a second baffle means extending from the opposite side of said shell part way across said space below said point of communication, a first electric heating element within said hollow member above the upper baffle means, a second electric heating element within said hollow member be-

tween said baffle means, a third electric heating element within said hollow member below the lower baffle means, and an electric circuit, including a multiple-position switch, for selectively supplying current to any one of said elements.

8. Generator means for absorption refrigerating apparatus including a vertically extending hollow member, a shell around said hollow member forming therewith an annular space, a tubular member connected to said space adjacent to one end thereof, a first baffle means extending from the side of said shell part way across said space immediately above the point of communication therewith of said tubular member, a second baffle means extending from the opposite side of said shell part way across said space below said point of communication, a first electric heating element within said hollow member above the upper baffle means, a second electric heating element within said hollow member between said baffle means, a third electric heating element within said hollow member below the lower baffle means, an electric circuit, including a multiple-position switch, for selectively supplying current to any one of said elements, said hollow member having a portion extending below said shell, a thermo-syphon pump in heat exchange relation with said portion, a fourth electric heating element within said portion, and a circuit for supplying current to said fourth element independently of the position of said switch.

9. In absorption refrigerating apparatus, generator structure providing a plurality of regions of refrigerant vapor expulsion arranged and connected to each other so that absorption solution from which refrigerant vapor has been expelled in one region flows to another region for additional expulsion of refrigerant vapor, evaporator structure providing a plurality of places in each of which cooling is effected, conduit means for connecting in parallel said regions of vapor expulsion and said places of cooling, means in said conduit means to effect liquefaction of refrigerant vapors, and heating means for said generator so constructed and arranged that the heating effect may be utilized primarily to effect expulsion of refrigerant vapor in one of a plurality of said regions or in a plurality of said regions.

10. In absorption refrigeration apparatus having a cooling element, an absorber, a generator, and connections including a vapor-liquid lift connecting the absorber and generator to provide a circuit for circulation of absorption solution, said generator comprising structure providing a plurality of regions in which refrigerant vapor is expelled from absorption solution, evaporator structure providing a plurality of places in each of which cooling is effected, conduit means for connecting in parallel said regions of refrigerant vapor expulsion and said places of cooling, means in said conduit means to effect liquefaction of refrigerant vapor, heating structure primarily effective for heating said regions of vapor expulsion, additional heating means primarily effective to effect heating of said vapor-liquid lift, and control means for controlling said heating structure and said additional heating means.

11. In absorption refrigerating apparatus as set forth in claim 10, in which said control means includes a first control for said heating structure, and a second control for said additional heating means which affects said first control.

12. In absorption refrigerating apparatus as set forth in claim 10, in which said control means includes a first control for said heating structure, and a second control responsive to a temperature condition affected by said cooling element.

13. In absorption refrigeration apparatus, a generator comprising a first elongated vessel, a second elongated vessel having one end connected to an end of said first vessel, conduit means for supplying absorption solution to said second vessel at the end thereof opposite to that connected to said first vessel, conduit means for withdrawing absorption solution from an end of said first vessel opposite to that connected to said second vessel, a heater capable of heating said vessels to cause expulsion of refrigerant vapor from absorption solution therein, and conduit means for withdrawing expelled refrigerant vapor separately from said vessels for condensation and evaporation to produce refrigeration.

14. In absorption refrigerating apparatus having an absorber, a generator connected to said absorber to form a circuit for circulation of absorption solution and including structure providing two chambers having vertical extent and connected at their lower ends, conduit means for conducting absorption solution from the absorber to the upper part of one of said chambers, conduit means for conducting absorption solution from the upper part of said other chamber to the absorber, heating means for causing expulsion of refrigerant vapor from absorption solution in said chambers, and conduit means for separately withdrawing expelled refrigerant vapor from said chambers for condensation and evaporation to produce refrigeration.

15. In absorption refrigerating apparatus having a cooling element, an absorber, a generator, and connections including a pump connecting the absorber and generator to provide a circuit for circulation of absorption solution, conduit means for connecting said cooling element and said generator, a condenser in said conduit means, a heater primarily effective to cause expulsion of refrigerant vapor from solution in said generator, means associated with said pump capable of effecting operation thereof, a first control means responsive to a condition affected by the refrigerating apparatus for controlling said means associated with said pump, and additional control means for controlling said heater, said heater being rendered inoperative when operation of said pump is stopped by said first-mentioned control means.

16. In an absorption refrigerating apparatus, a plurality of generators connected together so that absorption liquid from which refrigerant vapor has been expelled in one generator flows to another generator for additional expulsion of refrigerant vapor, a plurality of condensers, means for conveying refrigerant vapor in parallel from the generators to the condensers, a plurality of evaporators, means for conveying liquid refrigerant in parallel from the condensers to the evaporators, and means for controlling the generation of refrigerant vapor in said generators.

17. In an absorption refrigerating apparatus, a pair of generators connected together so that absorption liquid from which refrigerant vapor has been expelled in one generator flows to the other generator for additional expulsion of refrigerant vapor, a pair of evaporators, separate conduit means connecting the respective generators and evaporators together, a condenser dis-

posed in each conduit means, and heating means for heating each of said generators.

18. In absorption refrigerating apparatus having a cooling element, an absorber, a generator, and connections including a pump connecting the absorber and the generator to provide a circuit for circulation of absorption solution, conduit means for connecting said cooling element and said generator, a condenser in said conduit means, a heater primarily effective to cause expulsion of refrigerant vapor from solution in said generator, means associated with said pump capable of effecting operation thereof, and control structure for controlling operation of said

means associated with said pump and said heater, said control structure including a first movable control element for controlling said heater and a second control element movable independently of said first element for controlling said means associated with said pump, said control structure being so constructed and arranged that, when said means associated with said pump is rendered inoperative by said second control element, said heater is also rendered inoperative irrespective of the position of said first control element.

GUSTAV MARTEN BLOMQVIST.
